(57) **CLAIM**

The ornamental design for a bed sheet, as shown and described.

DESCRIPTION

FIG. 1 is a perspective view of a bed sheet showing our new design;

FIG. 2 is a top plan view thereof;

FIG. 3 is a bottom plan view thereof;

FIG. 4 is a front elevation view thereof, the rear elevation view being identical thereto;

FIG. 5 is a left side elevation view thereof, the right side elevation view being identical thereto;

FIG. 6 is a perspective view of the bed sheet turned inside out;

FIG. 7 is a top plan view of the bed sheet turned inside out;

FIG. 8 is a bottom plan view of the bed sheet turned inside out;

FIG. 9 is a front elevation view of the bed sheet turned inside out, the rear elevation view of the bed sheet turned inside out being identical thereto; and,

FIG. 10 is a left side elevation view of the bed sheet turned inside out, the right side elevation view of the bed sheet turned inside out being identical thereto.

1 Claim, 10 Drawing Sheets
